UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed June 3, 1922, Serial No. 565,727. Renewed March 7, 1927.

The present invention relates in general to multi-office telephone systems, but is more particularly concerned with automatic multi-office systems, and the general object of the 5 invention is to provide means whereby the names or numbers of exchanges in a multi-office system, which according to the Strowger plan would be assigned to offices in one geographical district, may be assigned to offices in more than one geographical district.

A particular object of the invention is to provide novel and improved switching equipment for accomplishing the above results and for increasing the flexibility of the inter-office 10 trunking in large multi-office systems.

It is especially desirable to accomplish the above results in view of the fact that a large number of multi-office manual systems are now being changed to automatic operation 15 and when a transition of this kind is made it is advisable to retain the old manual exchange names as well as the subscribers' numbers, wherever possible, in order to avoid undue confusion. In accordance with this plan, 20 when the automatic system is installed the calling devices have letter combinations in the finger holes in addition to the usual numbers so that the office names, that is the first two or three letters of each office name may 25 be dialled by calling subscribers, these letters forming part of the directory numbers 30 of the subscribers. When a large multi-office manual system is changed to automatic operation it is usually necessary to use the first three letters of the manual exchange 35 names as part of the directory numbers of the subscribers in order to secure proper selection of exchanges, the remaining part of the number consisting of four digits. Under 40 these conditions it will be appreciated that, as in the majority of cases the manual exchange names are promiscuously assigned, situations are encountered in which there is a conflict between the first one or two letters 45 in the names of exchanges in different districts, the letters of these names appearing in the same finger holes on the dial, and it becomes necessary to provide trunking arrangements of the kind indicated above to 50 handle connections to these exchanges. The present invention is designed to take care of trunking connections of this character very economically.

There are a number of other objects of the

invention, which together with those enumerated above, will be described in detail in the technical description which is to follow, taken in conjunction with the accompanying drawings forming part of this specification.

Referring now to the drawings comprising 60 Figs. 1-10, inclusive, Fig. 1 is a map of certain of exchanges in the system and the trunk lines interconnecting them. Fig. 2 is a view of the calling device dial. Fig. 3 shows the manner in which the detailed circuit drawings 65 are to be placed in order to follow the description of the operation. Fig. 4 shows the trunking and switches involved in typical connections shown in accordance with the map of exchanges, Fig. 2. Fig. 5-10, inclusive, 70 show by means of the conventional circuit diagrams enough of the apparatus to enable the invention to be readily explained and understood.

The invention is, of course, applicable to 75 various sizes of multi-office telephone systems; however, in the present case it has been illustrated in connection with a seven digit system, or one the ultimate capacity of which does not exceed ten million lines. In this 80 case the first three letters of the exchange names are used as part of the directory numbers of subscribers, the remaining portion consisting of four digits.

In a system of this size, there will probably 85 be a large number of main offices which will be grouped together to form districts, each district comprising about ten main offices. Each of the main offices in each district will be connected to every other main 90 exchange in the district by direct trunks; thus each district forms a complete trunking network. To handle calls between the various districts each main office in every district is connected by trunk lines to one of the 95 nearest offices in every other district of the system, these last mentioned main exchanges serving as switching centers for inter-district calls. Arriving at these so called switching centers, the incoming calls are then routed 100 through the inter-office trunking system in the same manner as a local district call. Since the first three letters dialled determine to what exchange the call is going, if the first two letters of offices in different districts are the same, it will be necessary to use trunk lines 105 extending to the districts in which these offices are located when a call is made to either of

fice, and to release one connection when the third digit is dialled, which digit finally determines to what exchange the call is going.

In describing the drawings the general layout of the system will first be explained with reference to the map of exchanges, Fig. 1. In this figure, there are shown three districts, which have been indicated on the drawings by the reference characters A, B, and C. All the main exchanges in districts A, B and C, are connected together by trunk lines, while each main exchange has trunk lines to one exchange in every other district; thus, the main office Lombard in geographical district B has trunk lines extending to all the main exchanges in district B, and to the main exchanges Grove and Main, in geographical districts A and C. Only a few of the main exchanges in each geographical district have been shown, but it will be understood that there may be as many as ten main offices in each district. The arrow heads on the trunk lines indicate whether they are a group of one way trunk lines or a group of two way trunk lines. Of course, for these two way trunk lines may be substituted two groups of one way trunk lines. Only a portion of the system has been illustrated, and it will be understood that there will be a large number of other districts in the system. By referring to the names of the exchanges in the various districts, Fig. 1 and the calling device dial, Fig. 2, it will be seen that there is a conflict in the names of the exchanges Larabee and Main in district C and Maburn in district A. This conflict will serve to bring out all the features of the invention.

Referring now to the trunking diagram shown in Fig. 4, the various trains of switches involved in typical connections in the trunking situation shown in the map, Fig. 1, are illustrated. To give a general understanding of the operation of the system, the manner in which calls are extended from the main office Center to the various other offices, will now be described with reference to Fig. 4.

For the purpose of the description, it will first be assumed that the subscriber at substation A in the Center office, desires to call a subscriber at substation A⁵ in the Larabee office. In order to accomplish this result, the calling subscriber will remove his receiver and operate his calling device for the number LA Rabee—467x, the numerical equivalent of Larabee being 517, as may be seen from the drawings. The letter x, as used in this combination of characters, and as it will be used subsequently, simply indicates that the final digit may be any digit from 1 to 0, so far as the trunking diagram is concerned, the individual bank contacts of the connector levels not being shown. When the receiver is removed at substation A the individual primary line switch C operates to select an

idle trunk line leading to a selector repeater, such as 1E. The selector repeaters such as 1E have associated with them switching discriminators such as the switching discriminator SD shown in the drawings and also the secondary line switches C⁴ and C³. The selector repeater 1E has an extra set of bank contacts and cooperating wipers. When the first digit L is dialled both sets of wipers of the selector repeater 1E are raised to the fifth level of bank contacts and are then rotated in search of trunk lines extending to secondary line switches such as C¹ and C². The secondary line switches C¹ and C² then operate to select trunk lines leading to second selectors in the main exchanges Grove and Main in districts A and C, respectively, these exchanges serving as switching centers for the districts A and C, respectively, for connections from Center exchange. It will be assumed that the trunk lines leading to the second selector 2E¹ in the Grove exchange and the second selector 2E in the Main exchange are the trunk lines selected. In response to the second character A called on the calling device at the calling substation, the second selectors 2E¹ and 2E in the Grove and Main exchanges, respectively, are operated to the first level of bank contacts. These selectors then operate to select trunk lines leading to idle third selectors. It will be assumed that the second selector 2E¹ selects the third selector 3E¹ in Grove exchange, and that the second selector 2E in the Main office selects the third selector 3E in the same office. The switching discriminator SD is also operated in accordance with the second digit of the called number and its wipers are raised opposite the first level of bank contacts. In response to the next character R, the selector repeater 1E operates to repeat the digits to the third selectors 3E¹ and 3E in the Grove and Main exchanges, respectively, and the wipers of these switches are raised opposite the seventh levels of bank contacts and are then rotated in search of idle trunk lines. In the Grove exchange, the seventh level of the third selectors are dead and consequently the trunk selecting operation of the third selector 3E¹ is without function. The third selector 3E in the Main exchange operates to select a trunk line extending through a repeater such as R to an idle incoming fourth selector in the Larabee exchange such as the selector 4E. The switching discriminator SD is also operated in accordance with the character R and as this character determines that the Larabee and not the Maburn office is being called the switching discriminator SD causes the trunk extending by way of the secondary line switch C¹ to be released. This operation also releases the switches 3E¹ and 2E¹ in the Grove exchange. In response to the four remaining digits of the called number, 467x, the fourth selector 4E, a fifth selec-

5E⁵ and a connector H⁵ in the Larabee exchange are operated to complete the connection to the line of the substation A⁵, the line relay of the selector repeater 1E repeating 5 the impulses to the line relay of the repeater R which in turn repeats these impulses to the switches 4E, 5E, and H.

It will now be assumed that the calling subscriber at substation A instead of desiring to connect with a subscriber at substation A⁵ in the Larabee office, desires to connect with the line of the substation A⁶ in the main office, whose number is MAIn-735x, the numerical equivalent of 15 MAI being 511 as is shown just below the office name in Fig. 4. In this case in response to the removal of the receiver and the dialling of the letters MA the connection will be extended as before. In response to 20 the third character I the wipers of the third selectors 3E¹ and 3E, instead of being raised to the seventh levels of bank contacts as was the case in the preceding connection, are raised to the first levels and are then rotated 25 in search of idle trunk lines. As before, the third selector 3E in the main office is the only one that has a useful function, that being to select an idle fourth selector such as 4E¹. The switching discriminator 30 SD in operating in response to the third character I, causes the release of the trunk line to Grove and the operated switches therein in the same manner as has already been described. In response to the four remaining 35 digits of the number 735x, the fourth selector 4¹, a fifth selector 5E¹, and a connector H¹ are operated to extend the connection to the line of the substation A⁶.

It will now be assumed that the calling 40 subscriber instead of desiring to call a subscriber at substation A⁶ in the Main office in district C, desires to call a subscriber at substation A³ in the Maburn office of district A, whose number is MABurn-634x. Under 45 these conditions the character B will be called for the third digit and the wipers of the third selectors 3E¹ and 3E in the Grove and Main offices, respectively, will be raised opposite the second levels of bank contacts. In this case the operation of the 50 selector 3E in the Main office is without function as the switching discriminator SD in operating in response to the third character B brings about the release of the line switch C², the trunk line extending to Main exchange, and the selectors 2E and 3E therein. In operating in response to the third digit, it will be assumed that the third selector 3E¹ in the Grove office selects the trunk 55 line shown in the drawings extending through the repeater R² and terminating in an incoming fourth selector 4E³ in the Maburn office. In response to the four remaining digits 634x of the called number, the 60 incoming fourth selector 4E⁵, a fifth selector

5E⁵ and a connector H⁵ are operated to complete the connection to the line of the substation A³.

It will now be assumed that the calling subscriber at Center exchange desires to call 70 a subscriber at substation A² in the Lombard exchange, whose number is LOMBard-445x. In this case, after the first character L is dialled, which will be the same as the digit M, being in the same hole on the 75 calling device, the calling subscriber will dial the character O whereupon the second selectors 2E¹ and 2E in the Grove and Main exchange, respectively, respond and their wipers are raised opposite the O level of 80 bank contacts. The switching discriminator SD is also operated in accordance with the digit O. The trunk selecting operation of the selectors 2E¹ and 2E are without function in the present instance as the 85 exchange Lombard is being called. In response to the third digit M the wipers of the switching discriminator SD are rotated in on the fifth bank contact set in the tenth level. The switching discriminator SD now causes 90 the trunk lines extending to the Grove and Main offices to be released as well as the operated switches therein, and in addition causes the line switch C⁴ associated with the selector repeater 1E to select a trunk line 95 extending to an idle fourth selector 4E³ in the Lombard exchange. The fourth selector 4E³, a fifth selector 5E¹ and a connector H² are operated in accordance with the remaining digits 445x, dialled by the calling 100 subscriber, to complete the desired connection.

It will now be assumed that the subscriber at substation A desired to extend a connection to a subscriber at substation A⁴ in the 105 Grove exchange, the directory number of this subscriber being GROve-648x. In response to the removal of the receiver the primary line switch C operates to select an idle selector repeater, which, we will assume, is the selector repeater 1E. When the calling device is 110 operated in accordance with the character G the wipers of the selector repeater 1E are raised opposite the fourth level of bank contacts and are then rotated in search of an idle 115 trunk line. It will be assumed that the trunk line extending to the line switch C¹ is the one selected. The secondary line switch C¹ now operates to select a trunk line extending to an idle incoming second selector in the Grove 120 exchange. It will be assumed that the selector 2E¹ in the Grove exchange is the one selected. As there are no offices in the A district having the second letter R or one in the same hole on the calling device dial, it is possible 125 to combine the trunk lines extending to the Grove exchange from the fourth and fifth levels of the selector repeaters such as 1E in Center office into one group. Accordingly the fourth and fifth levels of the selector re- 130

peaters such as 1E in the Center exchange are multiplied together. The calling subscriber at substation A in operating his calling device for the second digit R causes the first 5 selector 1E to repeat the impulses over the seized trunk line to the second selector 2E¹ in the Grove exchange. In accordance with these digits the wipers of the selector 2E¹ are brought opposite the seventh level of 10 bank contacts and are then rotated in search of an idle trunk line. It will be assumed that the third selector 3E¹ is the one selected and connected with by the second selector 2E¹. It will be noted that it is possible to use one 15 group of third selector switches such as 3E¹ to handle connections to both the Grove and Maburn exchanges for the reason that there is no conflict in the third digit of the exchange names of district A, these being in 20 separate finger holes on the dial. In response to the third digit O the wipers of the third selector 3E¹ are raised to the tenth level and are then automatically rotated to select an 25 idle trunk line leading to a fourth selector such as 4E¹. The switching discriminator SD responds to the second and third digits called in the same manner as before. However, as only one trunk line extending to the 30 Grove exchange has been seized there being no conflict between the first and second digits of Grove with any other exchange names the switching discriminator has no 35 switching function to perform. In response to the four remaining digits 648x of the called number, the fourth selector 4E¹, a fifth selector such as 5E¹ and a connector H¹ are operated to establish the connection with the line of the substation A¹.

It will now be assumed that the subscriber 40 at substation A desires to call a subscriber at substation A¹, the line of which terminates in the same exchange as that of the substation A, the directory number of this substation being CENter-245x. In response to 45 the removal of the receiver, the primary line switch C operates to select a trunk line extending to an idle selector repeater such as 1E. In response to the first character C the wipers of the selector repeater 1E are brought 50 opposite the second level of bank contacts and are then automatically rotated in search of an idle trunk line. In the situation shown in the drawings, there is no other office in the system having its first character in the same 55 hole on the calling device as the letter C. Therefore, the second level of the selector repeaters such as 1E are dead and the trunk hunting operation of this switch is without function.

60 Should there be other exchanges in the system having exchange names beginning with the letter C or one in the same finger hole of the calling device dial, the selector repeater 1E would function to select a trunk line to the office which serves as a switching

center on calls from Center exchange in the districts in which the desired exchange is located.

When the next two characters EN are dialled on the calling device, the wipers of 70 the switching discriminator SD are operated to the third level of bank contacts and are then rotated into engagement with the sixth contact set. The switching discriminator SD now causes the line switch C² to automatically 75 operate to extend the connection to a fourth selector such as 4E² in the Center office. Should a trunk line have been seized by the selector repeater 1E on the second level, this 80 trunk line would also be released by the operation of the switching discriminator in a manner similar to that already described. The fourth selector 4E², a fifth selector 5E² and a connector H² are operated in accordance with the four remaining digits 254x to 85 establish the connection with the line of the substation A¹.

From the above it will be seen that offices, which in the regular Strowger trunking system would be located in the same district, 90 may be located in different districts without regard to their names, and that a number of routes are tentatively employed to extend the connection to the desired line, the only one held being the one over which it is finally 95 determined that the connection is to be completed.

Referring now more particularly to the detailed circuit drawings, Figs. 5-10, inclusive, in Fig. 5 there is shown an automatic 100 substation A which is of the usual type having the calling device S. The line conductors 11 and 12 of the substation A terminate at an exchange in the individual line or trunk selecting switch C.

The line switch C is of the usual rotary type whose wipers have no normal position, always standing in engagement, when idle, with the bank contacts associated with the trunk line last used. The line switch C, in 110 common with a plurality of other line switches of the group has access to trunk lines extending to selector repeater switches, one of these trunk lines being shown in the drawings terminating in the bank contacts 115 28-30, inclusive, and extending to the selector repeater 1E, Fig. 5.

The selector repeater 1E is of the usual Strowger type of mechanical construction. There are some differences, however, that 120 will now be mentioned. The selector repeaters such as 1E are provided with two sets of bank contacts and an additional set of wipers. Thus, the selector repeaters have twenty levels instead of the usual ten. However, the switch shaft is only adapted to take ten steps and the wipers when rotated engage bank contacts in two levels. The selector repeaters such as 1E have access to 125 trunk lines extending to various exchanges 130

in the different districts through secondary line switches, such as C¹ and C², Fig. 6.

Associated with each one of the selector repeaters is a switching discriminator, such 5 as SD, Fig. 9. The switching discriminator SD in the present case is of the same mechanical construction as a Strowger connector switch and is adapted to respond to two digits. The wipers 520 and 521 of the 10 switching discriminator SD have access to 300 bank contact sets in ten levels. The switching discriminator is adapted to control the operation of the selector repeater 1E.

15 The secondary line switches C³ and C⁴, Fig. 9, are also permanently associated with the selector repeater 1E. These line switches are similar to the primary line switch C already described. The line switch C³ has access 20 to trunk lines extending to local fourth selectors in Center exchange, one of these being indicated under the reference character 4E², Fig. 10. The line switch C⁴ has access to trunk lines extending to incoming 25 fourth selectors in the Lombard exchange.

The trunk lines accessible to the selector repeater 1E terminate in outgoing secondary line switches, such as C¹ and C², Fig. 6. These line switches are similar to the primary line switch C and the secondary line switches C³ and C⁴. The line switch C¹ has access to trunk lines extending to incoming 30 second selectors in the Grove exchange in district A. The secondary line switch C² has access to trunk lines extending to incoming 35 second selectors in Main exchange of district C, one of these being shown in the drawings terminating in bank contacts 258-260, inclusive, and extending to the incoming second selector 2E, Fig. 7.

The incoming second selector 2E, Fig. 7, is of the usual Strowger two wire type, and has access to trunk lines extending to third selector switches in Main exchange, such as 45 the selector 3E, Fig. 7.

The third selector 3E, the circuits of which have only been indicated in the drawings, is similar to the second selector 2E in all respects except that in the third selectors 50 the release trunks are extended back so as to provide a holding circuit for the preceding second selectors, which are adapted to seize them. The third selectors such as 3E have access to local fourth selectors in 55 the Main exchange, such as the one indicated by the reference character 4E¹ and also to trunk lines extending to incoming fourth selectors in the Larabee exchange by way of repeaters. One of these latter trunk 60 lines has been shown in the drawings terminating in the bank contacts 355-357, inclusive, and extending by way of the repeater R to the incoming fourth selectors 4E, Fig. 8, in Larabee exchange.

65 The incoming fourth selector 4E is sim-

ilar to the incoming second selector 2E in the Main exchange and has access to trunk lines extending to local fifth selectors such as the selector 5E.

The selector 5E, Fig. 8, is similar to the 70 third selector 3E already described and is adapted to connect with trunk lines extending to connector switches in the Larabee exchange, one of these connectors being shown in the drawings at H.

75 The connector H is of the usual Strowger vertical and rotary type and is adapted to extend connections to local subscribers' lines in the Larabee exchange. One of the local lines, that of the substation A⁵, to which the 80 connector H has access is shown in the drawings terminating in bank contacts 474-476, inclusive.

The substation A⁵ is similar to the substation A already described. The line of 85 the substation A⁵ terminates at the exchange in the rotary line switch C⁵ in addition to the multiple bank contacts of the connector switches which have access to it.

The line switch C⁵ is identical in all respects 90 to the primary line switch C, Fig. 5.

The local fourth selectors in the Main exchange such as the selector 4E¹, Fig. 7, are similar to the third selectors such as 3E and have access to trunk lines extending to local 95 fifth selectors in the Main office.

These fifth selectors in turn are adapted to extend connections to local connector switches similar to the connector H, Fig. 10.

The connector switches, of course, have 100 access to local subscribers' lines in the Main office in the same manner as the connector H has access to the line of the substation A⁵ in the Larabee exchange.

The local fourth selectors such as 4E², the 105 local fifth selector such as 5E², and connector H, Fig. 10, in the Center exchange, are similar to corresponding selectors and connector switches that have been previously described and are adapted to complete connections in 110 Center exchange.

The line of the substation A¹ which has been shown accessible to the connector H³, Fig. 10, is one of the subscribers' lines in the 115 Center exchange.

The substation A¹ is similar to the substations A and A⁵, previously described, and the line switch C⁶ in which the line of this substation terminates, is similar to the primary line switch C, Fig. 5, in all respects.

Having described the drawings and the general manner in which connections are established from the subscriber at substation A in Center exchange in district B, to subscribers whose lines terminate in various other exchanges of districts A, B and C, the detailed circuit operations when these connections are extended will now be described with reference to the circuit drawings, Figs. 5-10, inclusive, 125 these drawings being laid out in the manner 130

shown in Fig. 4. In order to describe these operations, it will first be assumed, as in the general description, that the subscriber at substation A, whose line terminates in Center 5 exchange, desires to connect with the line of the substation A⁵ in the Larabee exchange, the directory number of this substation being LARabee—467x. In order to do this, the calling subscriber will remove his receiver 10 and operate his calling device S in accordance with the first three letters of Larabee, LAR, and then the numbers 467x.

When the receiver is removed at substation A, a circuit for the line relay 14 of the line 15 switch C is completed over the line conductors 11 and 12 in series. Relay 14, upon energizing, at its armature 24 completes a circuit which includes the switching relay 15 and the motor magnet 17 in series and at its armature 20 23 connects the test wiper 26 to the above circuit at a point midway between the switching relay and the motor magnet. The operation of the line switch C now depends upon whether the trunk line associated with the switch 25 wipers is busy or idle. Assuming the trunk line to be busy, there will be a ground potential upon the test contact engaged by the test wiper 26, and the motor magnet 17, which is supplied with direct ground by way of the 30 said test wiper, operates as a buzzer to advance the switch wipers 25—27, inclusive, step by step until they are brought into engagement with a set of bank contacts associated with an idle trunk line. However, we will 35 assume in the present case, that when the receiver is removed at substation A, the switch wipers of the line switch C are in engagement with the bank contacts associated with an idle trunk line, and it will be assumed further 40 that this trunk line is the one shown in the drawings terminating in bank contacts 28—30, inclusive. In this case the switching relay 15 is energized immediately after the energization of the line relay 14. Relay 15, upon operating, at its armature 19 places ground upon the test contact 29 of the seized trunk line and prepares a holding circuit for itself, at armatures 18 and 20 disconnects the line conductors 11 and 12 of the substation A from the 45 winding of the line relay 14 and from ground, respectively, and extends them by way of wipers 25 and 27, bank contacts 28 and 30, normally closed springs controlled by armatures 65 and 66, left hand windings of the repeating coil, through the upper and lower windings of the line relay 56 of the selector repeater 1E, to battery and to ground, respectively.

The line relay 56 is immediately energized 60 over the calling line loop and, upon operating, at its armature 85 completes a circuit for the slow acting relay 57. The relay 57, upon energizing, at its armature 90 opens a point in the circuit of the release magnet 61, at 65 the front contact of this armature prepares

the operating circuits of the selector repeater, and at armature 89 places ground upon the release trunk conductor 103, thereby establishing a holding circuit for the switching relay 15 of the primary line switch C. This 70 holding circuit may be traced from ground upon the release trunk conductor 103 by way of bank contact 29, test wiper 26, armature 19 and its front contact, through the winding of the switching relay 15, and thence through 75 the winding of the motor magnet 17 to battery. This holding circuit serves to maintain the switching relay 15 energized throughout the connection, and it will be understood that it is established before the slow acting line 80 relay 14 has had time to deenergize. A branch of this holding circuit also extends by way of the private normal conductor 22 to multiply connected test contacts in the banks of the connector switches which have access 85 to the line of the substation A, whereby the said line is protected from intrusion throughout the existence of the connection.

When ground is placed upon the release trunk conductor 103, another circuit is completed which extends from release trunk conductor 103, conductor 145, through the winding of the relay 504 of the switching discriminator SD, to battery. Relay 504 is energized over this circuit and, upon operating, opens the circuit of the release magnet 507 of the switching discriminator.

The calling subscriber at substation A may now operate his calling device in accordance with the first character L of the called number, whereby five interruptions are produced in the circuit of the line relay 56 of the selector repeater 1E. Relay 56, upon deenergizing in response to these interruptions, sends five impulses of current to the vertical magnet 62 of the selector repeater over a circuit extending from ground by way of armature 85 and its back contact, armature 90 and its front contact, armature 99 and its back contact, through the winding of the slow acting low resistance relay 58, and thence through the winding of the vertical magnet 62 to battery. Magnet 62 operates to raise the two sets of switch wipers 120—122, inclusive, and 124—126, inclusive, step by step until these wipers are placed opposite the fifth level of bank contacts. The slow acting relay 58 is energized in series with the vertical magnet 62 and upon the first vertical step of the switch shaft when the off normal springs are shifted, completes the circuit extending from ground by way of armature 89 and its front contact, front contact and armature 92, resting contact of off normal spring 84 and the said spring, and through the winding of the stepping relay 59 to battery. Relay 59, upon operating, at its armature 93 prepares a circuit for the rotary magnet 63, and at its armature 94 establishes a locking circuit for itself extending from ground upon release trunk 115 conductor 103.

conductor 103 by way of front contact and armature 94, back contact and armature 98, working contact of off normal spring 84 and said spring, and through the winding of the 5 relay 59 to battery. When the switch wipers are brought opposite the fifth level of bank contacts a cam on the switch shaft operates the spring 71 and causes it to engage its working contact. This operation prepares certain 10 circuits for the switching discriminator SD as will appear more fully later. Shortly after the termination of the vertical movement of the switch, the slow acting relay 58 deenergizes and a circuit is immediately closed for 15 the rotary magnet 63. Magnet 63, upon operating, rotates the two sets of switch wipers into engagement with the first set of bank contacts on the fifth level, and at its armature 98 opens the locking circuit of the stepping 20 relay 59. Relay 59 immediately deenergizes, opening the circuit of the rotary magnet 63, which deenergizes also. The operation of the switch 1E now depends upon whether the trunk lines with which the switch wipers are 25 associated are busy or idle. Assuming that both trunk lines are busy, there will be a ground potential upon the test contacts engaged by the test wipers 121 and 125, and a circuit will be thereby completed for the stepping 30 relay 59. Upon energizing, relay 59 establishes a locking circuit for itself, as before, and completes the circuit of the rotary magnet 63. Magnet 63 operates to advance the two sets of switch wipers into engagement 35 with the next two sets of bank contacts on the fifth levels, and at armature 98 opens the circuit of the stepping relay 59. Relay 59 thereby deenergizes opening the circuit of the rotary magnet 63 which deenergizes also. It 40 will be noted that both the test wipers 121 and 125 associated with each of the two sets of wipers are connected to the stepping relay 59. Therefore, the relay 59 and the rotary magnet 63 will continue to operate alternately 45 until both sets of switch wipers are associated with an idle trunk line. It will be assumed that the switch wipers 120-122, inclusive, are rotated into engagement with the bank contacts 130-132, inclusive, and that the 50 switch wipers 124-126, inclusive, are rotated into engagement with the bank contacts 140-142, inclusive, and it will be assumed further that the trunk lines associated with these contact sets are idle. Under these 55 conditions, immediately upon the two sets of wipers being brought into engagement with these bank contacts, the switching relay 60, which has been maintained short circuited during the preceding operations of the 60 switch, is energized in series with the stepping relay 59. The latter relay does not operate in series with the switching relay, due to the comparatively high resistance of the winding of the relay 60. Relay 60, upon energizing, 65 at armature 99 opens a point in the circuit of the vertical magnet 62, at the front contact of this armature prepares an operating circuit extending to the switching discriminator SD, at armature 97 places ground upon the test contacts 131 and 141 by way of 70 test wipers 121 and 125, and at armatures 95 and 96 places a bridge across the wipers 120 and 122 and 124 and 126, respectively, through contact springs 86 and 87 of the line relay 56. The line relay 201 of the secondary 75 line switch C¹ and the line relay 241 of the secondary line switch C² are immediately energized. The circuit of the line relay 201 may be traced as follows: from ground by way of armature 89 and its front contact, front contact and armature 97, armature 77 and its back contact, test wiper 121, test contact 131, trunk conductor 16, armature 206 and its back contact, and through the winding of the line relay 201 to battery. Relay 201, upon 80 energizing, at armature 235 completes a circuit for the switching relay 200 in series with the motor magnet 202, at its armature 234 connects the test wiper 215 to the above circuit at a point midway between the switching 85 relay and the motor magnet. The trunk selecting operation of the secondary line switch C¹ now takes place in the same manner as was described in connection with the operation of the primary line switch C. When an idle 90 trunk line is found, which, we will assume, is the trunk line terminating in bank contacts 218-220, inclusive, the switching relay 200 is immediately energized. It will be remembered that the trunk lines accessible to the secondary line switch C¹ extend to incoming 95 second selectors in the Grove exchange. Only two line conductors of the trunk line extend to the incoming second selector, as one of the functions of the selector repeater 1E is to repeat impulses over the trunk line. The test contacts associated with these trunk lines in the bank of the secondary rotary line switches such as C¹ are multiplied together. When a 100 trunk line is seized, a group potential is placed upon the multiplied test contact, being fed ahead from the operated selector repeater. The relay 200 of the secondary line switch C¹, upon operating, at its armature 105 207 places ground upon the test contact 219 to busy the seized trunk line, at armatures 205 and 208 extends the conductors 160 and 172 of the trunk line by way of wipers 214 and 216, bank contacts 218 and 220, over trunk conductors 232 and 234 to the upper and lower windings of line relay of the incoming 110 fourth selector in the Grove exchange, which has been indicated in the trunking diagram of Fig. 4, under the reference character 2E¹. The line relay 241 of the secondary line 115 switch C² which has been seized by the wipers 124-126, inclusive, of the selector repeater 1E, is energized over a circuit similar to the circuit of the line relay 201 of the line switch C¹. Upon energizing, relay 241 initiates the 120 125 130 135

trunk hunting operation of the secondary line switch C². When an idle trunk is found, which, it will be assumed, is the trunk line terminating in bank contacts 258-260, inclusive, the switching relay 240 is energized. Relay 240, upon operating, establishes a locking circuit for itself at armature 244, at armature 245 places ground upon the test contact 259 of the seized trunk line, at armatures 243 and 246 extends the trunk conductors 170 and 172 by way of wipers 252 and 254, bank contacts 258 and 260, trunk conductors 274 and 275, through the upper and lower windings of the line relay 300 of the incoming second selector 2E, Fig. 7, in Main office of district C.

5 The line relay 300 of the second selector 2E in Main exchange and the line relay of the incoming second selector in Grove exchange, are energized through contacts on the line relay 56 of the selector repeater 1E in Center office. The line relay of the incoming second selector 2E¹ in the Grove exchange, closes a circuit for its associated slow acting release relay, the latter operating to prepare the operating circuits of the incoming second selector in the usual manner. The line relay 300 of the second selector 2E, upon operating, closes the circuit of the slow acting relay 301. Relay 301, upon operating, at armature 25

10 309 opens a point in the circuit of the release magnet 31, at the front contact of this armature prepares a circuit for the vertical magnet 312, and at armature 308 prepares a circuit for the switching relay 304.

15 35 The calling subscriber at substation A may now operate his calling device in accordance with the second character A of the called number. By this operation, one interruption is produced in the circuit of the line relay 56 of the selector repeater 1E. By the operation of this relay, this interruption is repeated to the line relay 300 of the incoming second selector 2E in the Main office, and to the line relay of the second selector 2E¹ in the Grove office. The operation of the line relay 300 40

20 45 of the selector 2E¹ causes one impulse of current to be sent to the vertical magnet 312 in series with the slow acting relay 302. Magnet 312 operates to raise the switch shaft carrying the wipers 330-332, inclusive, opposite the first level of bank contacts. The slow acting relay 302 is energized in series with the vertical magnet and, upon the first vertical step of the switch, when the off normal springs are shifted, completes a circuit 50

45 55 for the stepping relay 303. Relay 303, upon operating, closes a locking circuit for itself at armature 318, and at armature 319 prepares a circuit for the rotary magnet 320.

60 65 A short interval after the termination of the vertical movement of the shaft, the slow acting relay 302 deenergizes and completes the circuit of the rotary magnet 320. Magnet 320 operates to rotate the switch wipers 330-332, inclusive, into engagement with the

first set of bank contacts on the first level, and opens the circuit of the relay 303 which deenergizes opening the circuit of the rotary magnet, which deenergizes also. The trunk selecting operation of the selector 2E continues in the same manner as was previously explained in connection with the trunk selecting operation of the switch 1E. When an idle trunk is found, which, it will be assumed, is the trunk line shown in the drawings terminating in bank contacts 334-336, inclusive, the switching relay 304 is energized in series with the stepping relay 303. Upon operating, relay 304, at armature 323 places ground upon the test contact 335 of the seized trunk line in order to busy it, at armatures 322 and 325 disconnects the trunk conductors 274 and 275 from the windings of the line relay 300 and at the front contacts of these armatures extends them to the line relay 340 of the third selector 3E.

75 80 85 The line relay 340 of the third selector 3E is immediately energized and operates to complete the circuit of the slow acting relay 341. Relay 341 operates to prepare the operating circuits of the third selector 3E and at armature 344 places ground upon the release trunk, whereby a holding circuit is established for the switching relay 304 of the incoming second selector 2E.

90 95 100 In a like manner, in response to the second character A, the wipers of the incoming second selector 2E¹, Fig. 4, in the Grove exchange, are raised to the second level of bank contacts and are then rotated until an idle trunk line is selected extending to a third selector, which it will be assumed, is the selector 3E¹ shown in the trunking diagram, Fig. 4.

105 110 The line relay of the third selector 3E¹ is immediately energized and closes the circuit of the associated slow acting release relay. By the operation of the release relay, the switch circuits are prepared and a holding circuit is established for the incoming second selector 2E¹.

115 120 125 The selector repeater 1E, in addition to repeating the interruptions produced by the calling device to the line relays of the selectors in Main and Grove exchanges, sends an impulse of current to the vertical magnet of the switching discriminator SD, Fig. 9, over a circuit extending from ground by way of armature 85 and its back contact, armature 90 and its front contact, armature 99 and its front contact, conductor 150, off normal springs 515 and 516, through the winding of the slow acting relay 503, and thence through the winding of the vertical magnet 506 to battery. The vertical magnet 506 of the switching discriminator SD operates to raise the switch shaft, carrying the wipers 520 and 521 opposite the first level of bank contacts. With the first upward movement of the switch shaft, the off normal springs are oper-

ated and the previously traced vertical magnet circuit is opened at the spring 516 but is immediately closed at the off normal springs 515 and 517 and at armature 512 on the slow 5 acting relay 503, which is energized in series with the vertical magnet. Shortly after the termination of the vertical movement of the switch, the slow acting relay 503 deenergizes and transfers the operating circuit to the 10 rotary magnet 505.

The calling subscriber may now dial the third character R of the desired number. This operation produces seven interruptions in the circuit of the line relay 56 of the selector repeater 1E. By the operation of relay 56 these interruptions are repeated to the line relay 340 of the third selector 3E in the Main office, and to the line relay of the third selector 3E¹ in the Grove office. The line relay 340 of the selector 3E controls the vertical movement of the switch, whereby the wipers 350-352, inclusive, are brought opposite the seventh level of bank contacts. Immediately after the vertical movement of the 25 switch, its trunk hunting rotary movement is initiated and continues, in the same manner as has been described, until an idle trunk is found. We will assume that the trunk line shown in the drawings terminating in bank 30 contacts 355-357, inclusive, is the one selected. The switching relay 342 is then energized, and operates to extend the connection to the line relay 370 of the repeater R.

The line relay 370 immediately energizes 35 and closes the circuit of the slow acting relay 371 at armature 375, and at armature 376 places a bridge across the trunk conductors 379 and 380, whereby a circuit is completed for the line relay of the incoming fourth 40 selector 4E, Fig. 8, in the Larabee exchange. The line relay of this selector operates to close the circuit of the slow acting release relay. The latter relay prepares the operating circuit of the selector in the usual manner. In 45 the Grove exchange the wipers of the third selector 3E¹ are raised to the seventh level of bank contacts and are then rotated in search of an idle trunk line. As the third digit determines that a subscriber whose line 50 terminates in the Larabee exchange is being called the trunk hunting operation of the selector 3E¹ is without function.

The line relay 56 of the selector repeater 1E, in operating in response to the third 55 character R, sends seven impulses of current to the rotary magnet 505 of the switching discriminator SD. Magnet 505 rotates the switch shaft carrying the wipers 520 and 521 step by step until the said wipers are brought 60 into engagement with the seventh set of bank contacts on the first level. The slow acting relay 502 is energized in series with the rotary magnet 505, and operates at its armature 511 to remove ground from the wipers 520 and 65 521 of the switching discriminator. Shortly

after the rotary movement of the switch terminates, a circuit may be traced extending from ground on release trunk conductor 103, conductor 145, back contact and armature 511, through the windings of relay 501, conductor 152, shaft controlled spring 71 and its working contact on the selector repeater 1E, conductor 151, wiper 520, bank contact 17, conductor 148, and through the lower winding of the relay 54 to battery. The relay 54 70

energizes over this circuit and, upon operating, at its armature 78 establishes a locking circuit for itself, at armature 77 disconnects ground from the test wiper 121 thereby opening the holding circuit of switching relay 200 75

of the secondary line switch C¹, and at armatures 76 and 79 closes a new bridge across the lower set of wipers 124 and 126, at the same time rendering the impulse springs 87 on the line relay 56 ineffective. The relay 501 is 80

energized in series with the lower winding of relay 54 and operates to open the rotary magnet circuit so that the switching discriminator SD will not be operated responsive to subsequent digits dialled by the calling subscriber. 85

The above mentioned bridge may be traced from switch wiper 124, front contact and armature 96, front contact and armature 76, back contact and armature 72, back contact 90 and armature 68, upper right hand winding 95

of the repeating coil, through the left hand winding of the electro-polarized shunt field relay 51, lower right hand winding of the repeating coil, front contact and armature 88 100 on line relay 56, armature 70 and its back contact, armature 75 and its back contact, armature 79 and its front contact, to wiper 126. When the holding circuit of the relay 200 of the secondary line switch C¹ is opened, this relay deenergizes to disconnect the trunk 105

conductors 160 and 162 from the trunk conductors 232 and 234 of the seized trunk line extending to Grove exchange. The circuit of the line relay of the third selector 3E¹ in Grove exchange is accordingly opened and this relay deenergizes to bring about the release of the third selector 3E¹ and the incoming second selector 2E¹. Another result of the deenergization of relay 200 is that ground 110 is disconnected from the test contacts such as 219 of the seized trunk line extending to Grove exchange, whereby the said trunk line is rendered accessible to other rotary secondary line switches in the group. 115

It will be remembered that the previously 120 traced bridge across the wipers 124 and 126 includes the spring 88 on the line relay 56, whereby the switches in the Grove exchange may be controlled.

When the calling subscriber at substation 125 A operates his calling device in accordance with the next digit 4, four interruptions are produced in the circuit of the line relay 56 of the selector repeater 1E and by the deenergization of this relay, are repeated to the 130

line relay 370 of the repeater R. This relay operates to repeat the four interruptions over the trunk conductors 379 and 380 to the line relay of the incoming fourth selector 4E, 5 Fig. 8, in the Market exchange. The resulting operations of the line relay of the fourth selector cause the switch wipers 400-401, inclusive, to be brought opposite the fourth level of bank contacts. A short time after the 10 end of the vertical movement of the fourth selector, its trunk hunting operation is initiated and its switch wipers are automatically rotated until they are brought into engagement with the bank contacts associated with 15 an idle trunk line, which, it will be assumed, are the bank contacts 404-406, inclusive. Immediately upon the switch wipers engaging this set of bank contacts, the switching relay of the fourth selector 4E is energized to 20 extend the connection to the line relay of the fifth selector 5E.

The line relay of the fifth selector operates immediately to close the circuit of its associated slow acting relay. The latter relay, 25 upon operating, establishes the usual holding circuit for the incoming fourth selector 4E and also prepares the fifth selector 5E for operation.

The calling subscriber may now operate his 30 calling device for the next digit of the desired number. The operation of the calling device serves to produce six interruptions in the circuit of the line relay 56 of the selector repeater 1E. The resulting deenergizations of this 35 relay repeat the six impulses to the line relay of the repeater R. As before, the line relay 370 of the repeater R then repeats the six interruptions to the line relay of the fifth selector 5E. The line relay of the fifth selector 40 5E, in operating in response to these interruptions, controls the vertical magnet in stepping the wipers 410-412, inclusive, of the fifth selector to the sixth level of bank contacts. Shortly after the termination of the 45 vertical movement of the switch its rotary movement is initiated and takes place until the switch wipers are associated with the bank contacts of an idle trunk line. It will be assumed that the trunk line terminating in 50 the bank contacts 414-416, inclusive, is the one selected and connected with by its selector 5E. Under these conditions, the switching relay of the selector 5E energizes to extend the connection to the line relay 421 55 of the connector H.

The relay 421 is immediately energized and, upon operating, at its armature 438 closes the circuit of the slow acting relay 422. Upon operating, the latter relay at 60 armature 441 opens the release magnet circuit, at the front contact of this armature prepares the impulsive circuits of this connector, at armature 440 prepares certain circuits in the connector H, and at armature 65 439 places ground upon the release trunk con-

ductor 465, thereby establishing a holding circuit for the fifth selector 5E and the fourth selector 4E.

As the trunk line extending to the Grove exchange has been released, the operation of 70 the armature 36 of the line relay 56 in response to the digit 6, has no function. Also, as the switching discriminator SD has performed its function, it also does not operate further. 75

When the calling device at substation A is operated in accordance with the next digit 7 of the desired number, seven interruptions are produced in the circuit of the line relay 56 of the selector repeater 1E and, by the operations of this relay and the operations of the line relay 370 of the repeater R, these interruptions are repeated to the line relay 421 of the connector H. The line relay 421 of the connector H deenergizes a corresponding 85 number of times, and seven impulses of current are sent to the vertical magnet 428, the first impulse traveling over the following circuit: ground by way of armature 438 and its back contact, armature 441 and its front contact, off normal springs 443 and 445, through the slow acting relay 423, and thence through the winding of the vertical magnet 428 to battery. The above is the circuit over which 90 the first vertical magnet impulse is transmitted. However, upon the first vertical movement of the switch shaft the off normal springs are shifted and the remaining impulses to the vertical magnet traverse a new 95 circuit, which is the same as the one previously traced except that it includes the off normal springs 443 and 444 and armature 450 on the slow acting relay 423, this relay being 100 now energized. The vertical magnet 428 operates to raise the switch shaft carrying the 105 wipers 470-472, inclusive, step by step until they are brought opposite the seventh level 110 of bank contacts. The slow acting relay 423 is energized in series with the vertical magnet and, as indicated before, operates at armature 450 to maintain the circuit of the vertical magnet intact throughout the vertical movement of the switch shaft. Shortly after the 115 cessation of the vertical movement, the slow acting relay 423 deenergizes to prepare a circuit for the rotary magnet 435. 120

The calling subscriber may now operate his calling device in accordance with the next final digit of the desired number. By this operation a series of interruptions is produced 125 in the circuit of the line relay 56 of the selector repeater 1E in the Center exchange. The line relay 56 operates to repeat these series of interruptions to line relay 370 of the repeater R. By the operation of the latter relay, this last series of interruptions is produced in the circuit of the line relay 421. The deenergization of line relay 421 in response to these interruptions sends a plurality of impulses corresponding in number 130

to the digit dialed to the rotary magnet 435 over the following circuit: ground through armature 438 and its back contact, armature 441 and its front contact, off normal springs 443 and 444, armature 450 and its back contact, back contact and armature 455, armature 462 and its back contact, and through the winding of the rotary magnet 435 to battery. Magnet 435 operates to rotate the shaft of the switch step by step until the wipers 470-472, inclusive, are brought into engagement with the set of bank contacts associated with the line of the called substation A⁵, which, it will be assumed, are the bank contacts 474-476, inclusive. The slow acting relay 426 is energized in multiple with the rotary magnet 435, and at armature 457 operates to connect the test wiper 471 to the test relay 425, and at armature 458 short circuits the contact springs comprising armature 455 and its back contact on the test relay 425, so as to maintain the circuit of the rotary magnet closed while the wipers of the switch are being rotated over bank contact sets associated with busy lines. The operation of the connector H now depends upon whether the called line is busy or idle.

Assuming first that the called line is busy, there will be a ground potential upon the test contact 475 engaged by the test wiper 471. A circuit is thereby completed for the test relay 425. Upon energizing, relay 425 at armature 454, closes a point in its locking circuit which is completed immediately after the deenergization of slow acting relay 426, at its armature 455 opens a point in the rotary magnet circuit, and at armature 456 connects a lead from the busy signalling machine to the lower heavy talking conductor, whereby the calling subscriber is informed that the desired line is busy. The subscriber at substation A will now replace his receiver. By this operation the switches used in extending the connection to the line of the substation A⁵ in the Larabee exchange are released in a manner which will be described subsequently.

It will now be assumed that the line of the substation A⁵ is idle when the switch wipers 470-472, inclusive, are brought into engagement with the set of bank contacts 474-476, inclusive. Under these conditions, there will be no ground potential upon the test contact engaged by the test wiper 471 and no circuit will be completed for the test relay 425. Then, shortly after the termination of the rotary movement of the switch, the slow acting relay 426 deenergizes and a circuit is completed extending from ground by way of front contact and armature 440, armature 454 and its back contact, through the upper winding of switching relay 427, back contact and armature 457, test wiper 471, test contact 475, private normal conductor, through the winding of the switching relay 480 of the line switch C⁵, and thence through the winding of

the motor magnet 482 to battery. The switching relays 427 and 480 are energized over this circuit. However, due to a mechanical locking device controlled by the armature of the line relay 481 of the line switch C⁵, the switching relay 480 only partially operates its armatures, enough to disconnect the line of the called substation from its normal battery and ground connections in the line switch C⁵.

In the connector H, the switching relay 427, upon energizing, at its armature 461 establishes a locking circuit for itself, at armature 462 opens the circuit of the rotary magnet, at armature 460 places direct ground upon the test contact 475, and at armatures 459 and 463 completes the signalling circuit. Ringing current from the generator GEN is now intermittently projected out on the called line until the receiver is removed at substation A⁵.

When the receiver is removed at substation A⁵, a circuit is completed for energizing the ring cut off relay 424. Upon operating, relay 424, at its armature 452 establishes a locking circuit for itself, at armatures 451 and 453 disconnects the ringing current, and at the front contacts of these armatures finally completes the talking connection. Talking current is supplied to the called substation from the windings of the back bridge relay 420 which is, of course, energized over the called line loop. Relay 420, upon energizing, at its armatures 436 and 437 operates to reverse the connections to the line relay 421 with regard to the trunk conductors 379 and 380, whereby the direction of current flow over these conductors is reversed. As the current flow in the left hand winding of the electro-polarized shunt field relay 372 in the repeater R is now in the same direction the current flow in its polarizing left hand winding, the armatures 396 and 397 of this relay will be attracted and the direction of current flow over the trunk conductors 274 and 275 will be reversed, thereby causing the electro-polarized shunt field relay 51 in the selector repeater 1E to operate. Upon operating, the electro-polarized relay 51 closes the circuit of the reversing relay 50. The latter relay, upon operating, reverses the current flow over the calling line for supervisory or metering purposes, as the case may be. Conversation may now take place between the calling subscriber at substation A in the Center exchange and the called subscriber in substation A⁵ in the Larabee exchange, talking current being supplied to the substation A from the windings of the line relay 56 in the selector repeater 1E. The talking circuit may be readily traced, as it is indicated by the heavy conductors in the drawings.

When the conversation is terminated, the calling subscriber will replace his receiver on the switch-hook. This operation opens the circuit of the line relay 56 of the selector repeater 1E, which deenergizes, opening the cir-

cuit of the slow acting relay 57 and also the circuit of line relay 370 of the repeater R in the Main exchange. The slow acting relay 57, upon deenergizing, closes the circuit of release magnet 61 at armature 90, and at armature 89 removes ground from the release trunk conductor 103, whereby the holding circuit of the switching relay 15 of the primary line switch C is opened. The deenergization of relay 15 restores the primary line switch to normal. The removal of ground from the release trunk conductor 103 also opens the circuit of relay 504 in the switching discriminator SD. Relay 504, upon deenergizing, closes the circuit of the release magnet 507. Magnet 507 of the switching discriminator operates to restore the switching discriminator to normal. The circuit of the release magnet being opened by off normal springs when the switch shaft reaches normal position. The release magnet 61 of the selector repeater 1E, of course, operates to restore the switch shaft carrying the two sets of switch wipers to normal in the usual manner. Another result of the deenergization of the slow acting relay 57 is that ground is removed from the switch wiper 125 whereby the holding circuit of the switching relay 240 of the secondary line switch C² is opened and this relay deenergizes to restore this switch to normal.

As the circuit of the line relay 370 of the repeater R in Main exchange has been opened by the deenergization of the line relay 56 of the selector repeater 1E, this relay deenergizes and, upon so doing, at armature 375 opens the circuit of the slow acting relay 371, and at armature 376 opens the circuit of the line relay 421 of the connector H in the Larabee office. The deenergization of slow acting relay 371 in the repeater R removes ground from the release trunk conductor 361 thereby opening the holding circuit of the switching relays 304 and 342 of the second selector 2E and the third selector 3E, respectively, in Main office. By the energization of these switching relays the respective switches are restored to their normal position.

The circuit of the line relay 421 of the connector H being opened, this relay deenergizes, and opens the circuit of its associated slow acting release relay 422. The latter relay, upon retracting its armatures, closes the circuit of the release magnet 429 of the connector H at armature 441, and at armature 439 opens the locking circuit of the ring cut off and switching relays 424 and 427, respectively, and also at this same armature removes ground from the release trunk conductor 465, whereby the holding circuits of the fourth selector 4E and the fifth selector 5E in the Larabee exchange are opened. By the deenergizations of the switching relays in these switches the fourth and fifth selectors 65 are restored to normal. The release magnet

429 of the connector H operates to release the switch shaft of the connector, the circuit of the release magnet being opened at off normal springs when the switch shaft reaches its normal position.

The release of the connector H causes ground to be removed from the test contact 475 of the called line, whereby the circuit of the switching relay 480 of the called line switch C⁵ is opened. Relay 480, upon deenergizing restores the line switch C⁵ to normal.

In the above manner all the apparatus involved in the extension of a connection from a subscriber at substation A in the Center exchange to the line of the substation A⁵ in 80 the Larabee exchange is released.

It will now be assumed that the calling subscriber at substation A, instead of desiring to call the subscriber at substation A⁵ in the Larabee exchange, desires to extend a connection to the subscriber at substation A⁶ in the Main exchange, whose number is MAIn—736x. Under these conditions, the subscriber at substation A instead of operating his calling device for the third character R, as was previously the case, will operate his calling device for the character I. By this operation one interruption is produced in the circuit of the line relay 56 of the selector repeater 1E, and by the deenergization of this relay is repeated to the line relay 340 of the third selector 3E in the Main exchange.

The line relay 340 of the third selector 3E controls the operation of the switch, whereby the wipers 350-353, inclusive, are brought opposite the first level of bank contacts. Shortly after the termination of the vertical movement of the switch, the trunk hunting operation takes place, whereby the switch wipers are brought into engagement with a set of bank contacts associated with an idle trunk line, which, we will assume, are the bank contacts 358-360, inclusive. Immediately upon the switch wipers engaging this set of bank contacts, the switching relay 342 of the third selector 3E is energized and operates to extend the connection to the line relay of the fourth selector 4E¹ in the Main office.

In the selector repeater 1E, the deenergization of the line relay in response to the third character I causes one impulse of current to be sent to the rotary magnet 505 of the switching discriminator SD in series with the slow acting relay 502. The rotary magnet 505 of the switching discriminator operates to rotate the switch shaft carrying the switch wipers 520 and 521 into engagement with the first set of bank contacts on the first level. Upon the deenergization of the slow acting relay 502, which is energized in series with the rotary magnet, ground is placed upon the wiper 520 of the switching discriminator SD, whereby a circuit is completed extending from the said wiper, bank contact 11, conductor 148, and through the lower winding of relay 54 130

to battery. This relay, upon operating, establishes a locking circuit for itself, as before, and opens the holding circuit of the switching relay 200 of the secondary line switch C^1 and also closes another bridge across the wipers 124 and 126 which includes the right hand windings of the repeating coil, and the left hand winding of the electro-polarized shunt field relay 51. The switching relay 200 of the secondary line switch C^1 , upon deenergizing, brings about the release of the second selector $2E^1$ and the third selector $3E^1$ in the Grove exchange in the same manner as before. The relay 501 is energized in series with the lower winding of relay 54 and operates at its armature 510 to open the circuit of the release magnet 505 so that the said magnet will not receive any impulses caused by the deenergization of the line relay 56 of the selector repeater 1E in response to subsequent digits dialled.

In response to the next digit 7 dialled by the calling subscriber the line relay 56 of the selector repeater repeats the interruptions to the line relay 385 of the fourth selector $4E^1$. Accordingly the wipers 390-392, inclusive, of the selector $4E^1$ are raised opposite the seventh level of bank contacts by the vertical magnet under control of the line relay 385. The trunk selecting operation of the fourth selector $4E^1$ is now initiated and continues until the switch wipers are associated with the bank contacts of an idle trunk line, which it will be assumed, is the bank contact set comprising contacts 393-395, inclusive. The switching relay 387 of the fourth selector immediately energizes and extends the connection to the line relay of the fifth selector in the Main office.

Responsive to three remaining digits 36x of the called number, a fifth selector $5E^1$ and a connector H^1 , (Fig. 4) are operated in the same manner as was the fifth selector 5E and the connector H, to extend the connection to the line of the substation A^6 in Main exchange.

When the conversation is terminated the release of the connection is brought about by the replacement of the receiver at substation A in substantially the same manner as has been described in the preceding connection.

We will now assume that the subscriber at substation A instead of desiring to connect with the line of the substation A^6 in the Main office of district C, desires to communicate with the subscriber at substation A^3 in the Maburn office in district A. In this case, the subscriber instead of operating his calling device for the third character I as just described, will dial the character B. By this operation two interruptions are produced in the circuit of the line relay 56 of the selector repeater 1E. Relay 56, operates to repeat these two impulses to the line relay 340 of the third selector $3E$ in Main exchange and to the line relay

of the third selector $3E^1$ in the Grove exchange. By the operation of the line relay 340 of the third selector $3E$, the switch wipers are brought opposite the second level of bank contacts and the rotary movement of the switch is automatically initiated. As the third digit determines that the Maburn office is being called instead of an office in the C district as before, the trunk hunting operation of the selector $3E$ is without function.

The line relay of the third selector $3E^1$ in the Grove office operates to control the vertical magnet in stepping the wipers of the switch to the second level of bank contacts, whereupon the trunk selecting operation of the selector $3E^1$ takes place in the usual manner. It will be assumed that the trunk line shown in the trunking diagram of Fig. 4 terminating in the incoming fourth selector $4E^5$ in the Maburn office, is the one selected. By the energization of the switching relay of the third selector $3E^1$ the connection is extended by way of the repeater R^2 to the fourth selector $4E^4$ in the Maburn office.

Adverting to the operation of the selector repeater 1E another result of the deenergizations of the line relay 56 in response to the third character B, is that two impulses of current are sent to the rotary magnet 505 of the switching discriminator SD in series with the slow acting relay 502. Magnet 505 operates to rotate the switch wipers 520 and 521 into engagement with the second set of bank contacts on the first level. Shortly after the cessation of the rotary movement of the switching discriminator SD, the slow acting relay 502 deenergizes thereby placing ground upon the wipers 520 and 521. A circuit may now be traced extending from the grounded wiper 520, bank contact 12 of the switching discriminator, conductor 149, and thence through the lower winding of the relay 55 in the selector repeater 1E to battery. Relays 501 and 55 are energized over this circuit. Relay 501 simply opens the rotary magnet, as before. Relay 55, upon operating, establishes a locking circuit for itself at armature 82, at armature 81 removes ground from the test wiper 125 thereby opening the holding circuit of the switching relay 240 of the secondary line switch C^2 , at armatures 80 and 83 disconnects the bridge across the wipers 120 and 122 of the selector repeater 1E and substitutes therefor another bridge including the right hand winding of the repeating coil, and the left hand winding of the electro-polarized shunt field relay 51, together with the impulsing contact 88 on the line relay 56.

The deenergization of the switching relay 240 of the secondary line switch C^2 restores this line switch to normal position, thereby removing ground from the test contact 259 of the seized trunk line comprising conductors 274 and 275 whereby the said trunk line is rendered accessible to other line switches so that it may be used

again. Another result of the deenergization of the switching relay 240 is that the circuit of the line relay 340 of the third selector 3E in Main office is opened. Upon deenergizing, 5 relay 340 opens the circuit of the slow acting relay 341. The latter relay, upon retracting its armatures, opens the holding circuit of the incoming second selector 2E and also closes the circuit of its own release magnet. In this 10 manner the operated switches in the Main office are released as is the trunk line from Center office to Main office.

When the next four digits 634x are dialled, 15 the line relay 56 of the selector repeater 1E operates to repeat each digit to the line relay of the repeater R² in the Grove exchange. The line relay of the repeater R² then repeats these digits over the trunk line to the Maburn exchange whereby a fourth selector such 20 as 4E⁵, a fifth selector such as 5E⁵, and a connector such as H⁵ are operated to extend the connection to the line of the desired substation A³ in the Maburn exchange.

The operation of these switches in response 25 to the last four digits is similar to the operation of the fourth selector 4E, the fifth selector 5E and the connector H, in the Market exchange, which has been previously explained.

30 At the termination of the conversation, the calling subscriber at substation A will replace his receiver upon the switch-hook whereby the connector H⁵, the fifth selector 5E⁵, the fourth selector 4E⁵, the third selector 3E¹, the second selector 2E¹, the secondary line switch C¹, the selector repeater 1E, the switching discriminator SD, and the primary line switch C are released in a manner similar to that described hereinbefore.

40 It will now be assumed that the subscriber at the calling substation A desires to obtain a connection with a subscriber at substation A² in the Lombard exchange, instead of the substation A³ in the Maburn exchange, the 45 number of which is LOMBard—445x. In order to do this, the subscriber at substation A will operate his calling device for the character L, which is, of course, the same as the character M being in the same hole on the calling 50 device dial and consequently the operation of the selector repeater 1E and the line switches C¹ and C² is the same as before. In response to the dialling of the second character O, ten 55 interruptions are produced in the circuit of the line relay 56 of the selector repeater 1E and by the operation of this relay are repeated to the line relay 300 of the second selector 2E in the Main office and the line relay of the second selector 2E¹ in the Grove office. The 60 line relay 300 of the second selector 2E in the Main office raises the switch wipers 330-332, inclusive, to the tenth level of bank contacts and the trunk selecting operation of the switch then takes place. The line relay of 65 the second selector 2E¹ steps the switch shaft

carrying the switch wipers of the second selector 2E¹ in the Grove exchange to the tenth level of bank contacts, the trunk hunting operation of the selector 2E being then initiated. As the second character 0 determines that the 70 Lombard exchange is being called the trunk hunting operation of the selector 2E¹ in the Grove exchange and the operation of the second selector 2E in the Main exchange is without function in the present instance. 75

The line relay 56 of the selector repeater 1E in operating in response to the second character 0 of the called number, also causes the wipers 520 and 521 of the switching discriminator SD to be brought opposite the tenth 80 level of bank contacts.

When the next character M is dialled five 85 interruptions are produced in the circuit of the line relay 56 of the selector repeater 1E. Relay 56 operates as before, to repeat these interruptions over the trunk lines extending to the Main and Grove offices. However, these operations serve no useful purpose in the present case.

The line relay 56, in response to the third 90 character M, also sends five impulses of current to the rotary magnet 505 of the switching discriminator SD, whereby the switch wipers 520 and 521 are rotated into engagement with the fifth set of bank contacts in the tenth 95 level. The slow acting relay 502 energizes in series with the rotary magnet 505. Shortly after the cessation of the rotary magnet impulses relay 502 deenergizes and places ground upon the wipers 520 and 521. By the 100 grounding of wipers 520 a circuit is completed extending from the said wipers, bank contacts engaged by said wipers in the switching discriminator, conductors 148 and 149, through the lower windings of relays 54 and 55 to battery. Both these relays are energized in series with the relay 501 of the switching discriminator. Relay 54, upon operating, removes ground from the test wiper 121 thereby opening the holding circuit of switching 110 relay 200 of the secondary line switch C¹. These operations cause the deenergization of the relay 200 and the release of the trunk line extending to Grove exchange, as well as the operated switches therein. Relay 55, upon 115 energizing, establishes a locking circuit for itself at armature 82, and at armature 81 disconnects ground from the test wiper 125 thereby opening the circuit of the switching relay 240 of the secondary line switch C². The switching relay 240 of the secondary line switch deenergizes thereby freeing the trunk line extending to the Main office and at the same time initiating the release of the operated switches therein. By the grounding of 120 wiper 521 of switching discriminator, a circuit is completed extending from the said grounded wiper by way of lower bank contact 05, conductor 146, through the winding of the relay 52 to battery. Relay 52, upon 125

130

energizing, places ground upon the conductor 154 at armature 69, at armatures 68 and 70 disconnects both sets of wipers from the talking conductors in the selector repeater 1E and 5 extends these talking conductors over the conductors 153 and 155 to the secondary line switch C⁴. The grounding of conductor 154 causes the line relay 575 of the secondary line switch C⁴ to be energized. Relay 575, upon 10 operating, initiates the trunk selecting movement of the secondary line switch C⁴, this taking place in the usual manner. When an idle trunk is found, which, it will be assumed, is the trunk line terminating in bank contacts 15 590-592, inclusive, the switching relay 576 is energized to place ground upon the test contact of the seized trunk line in order to busy it, and also to connect the above mentioned talking conductors to the trunk conductors 20 595 and 596 extending to the line relay of an incoming fourth selector, such as 4E³ (see trunking diagram) in the Lombard exchange.

When the next digit 4 is dialled, four interruptions are produced in the circuit of the 25 line relay 56 of the selector repeater 1E and these impulses are repeated to the line relay of the incoming fourth selector 4E³ in the Lombard exchange. The line relay of the fourth selector 4E³ controls the operation 30 of the vertical magnet of this switch in raising the switch wipers opposite the fourth level of bank contacts. The trunk selecting movement of the switch is then started and continues until the switch wipers are brought into engagement with the 35 bank contacts associated with an idle trunk line, whereupon the switching relay of the selector 4E is energized. The switching relay, upon operating, extends the connection 40 to an idle fifth selector such as 5E³.

In response to the three remaining digits 45x of the called number, the fifth selector 5E³ and a connector such as H² are operated to complete the desired connection.

45 All the operated switches involved in this connection are released by the replacement of the receiver at the calling substation in a manner similar to that already described.

It will now be assumed that the calling 50 subscriber at substation A desires to extend a connection to a subscriber at substation A⁴ in Grove exchange, whose number is GROve-648x. In order to do this, the calling subscriber removes his receiver and operates his calling device in accordance with 55 these characters.

When the receiver is removed, the line relay 14 is energized over the calling line loop. Relay 14, upon energizing, causes the line switch C to select an idle trunk line in the usual manner. It will be assumed that the trunk line shown in the drawings terminating in bank contacts 28-30 inclusive, is the one selected. The switching relay 15 of the

primary line switch immediately energizes 65 thereby extending the calling subscriber's line to the line relay 56 of the selector repeater 1E.

Relay 56 immediately energizes and operates to close, at its armature 83, the circuit 70 of the slow acting relay 57. Relay 57 prepares the operating circuits of the selector repeater and at armature 89 places ground upon release trunk conductor 103, whereby a holding circuit is established for the switching relay 15 of the primary line switch.

When the calling device is operated in accordance with the first character G, four interruptions are produced in the circuit of the line relay. Relay 56, upon deenergizing, 80 in response to these series of interruptions, sends four impulses of current to the vertical magnet 62 in series with the slow acting relay 58. Magnet 62 operates to raise the switch shaft carrying the switch wipers step 85 by step until the said wipers are brought opposite the fourth level of bank contacts. The slow acting relay 58 is energized in series with the vertical magnet and upon the first upward movement of the switch shaft, 90 when the off normal springs are shifted, completes a circuit for the stepping relay 59. Relay 59 prepares the circuit of the rotary magnet and establishes a locking circuit for itself. A short interval after the termination 95 of the vertical movement of the switch, the slow acting relay 58 deenergizes to complete the circuit of rotary magnet. Magnet 63 operates to rotate the two sets of switch wipers into engagement with the first set of 100 bank contacts on the fourth level, at the same time opening the circuit for the stepping relay 59, which deenergizes, opening the circuit of the rotary magnet 63, which deenergizes also. As there is no conflict between 105 the office names in various districts in the present case, only the upper set of bank contacts are connected to trunk lines, the lower level of bank contacts being dead. Also, as there is no conflict between the second 110 character in the exchange names in district A, it is possible to combine two groups of trunk lines into one, the fourth and fifth levels of bank contacts in the selector repeater such as 1E are accordingly multiplied together. The trunk selecting operation of the selector repeater 1E now takes place in identically the same manner as has been described hereinbefore. When an idle trunk is found, which, it will be assumed, is the trunk 115 line terminating in bank contacts 134-136, inclusive, the switching relay 60 of the selector repeater is energized to place ground upon the test wiper 121 and to place a bridge across the wipers 120 and 122. By the 120 grounding of wiper 121 a circuit is completed for the line relay 201 of the secondary line switch C¹. This relay energizes to cause

125

the secondary line switch C^1 to select an idle trunk line, which, we will assume, is the trunk line terminating in bank contacts 218-220, inclusive. The switching relay 200 5 is operated to place ground upon the test contact 219 in order to busy the seized trunk line and to establish a locking circuit for itself. An additional result of the energization 10 of the line relay 200 is that a repeating circuit is closed across the conductors 232 and 234.

In response to the next character R of the 15 called number, seven interruptions are produced in the circuit of line relay 56 of the selector repeater 1E, and are repeated to the line relay of the incoming second selector 2E¹ in the Grove exchange. By the operation 20 of the line relay 2E¹, the wipers of the selector are brought opposite the seventh level of bank contacts and are then automatically rotated 25 into engagement with the bank contact set associated with a trunk line extending to an idle third selector switch, such as 3E¹. The seven deenergizations of the line relay 56 in response to the second character R, 30 cause the wipers 520 and 521 of the switching discriminator SD to be raised opposite the seventh level of bank contacts.

When the next character 0 is dialled, the 35 circuit of the line relay 56 is opened ten times by the operation of the calling devices S. The line relay 56 deenergizes ten times to repeat the interruptions to the line relay of the third selector 3E¹ in the Grove exchange. By 40 the operation of the line relay of the third selector, the wipers of this switch are raised to the tenth level of bank contacts, after which they are automatically rotated until brought into engagement with the bank contacts associated with an idle trunk line, 45 which, it will be assumed, is the one shown in the drawings extending to the fourth selector 4E¹.

The line relay 56 also sends ten impulses 50 of current to the rotary magnet 505 of the switching discriminator SD in series with the relay 502. Magnet 505 operates to rotate the wipers 520 and 521 into engagement with the tenth contact set on the seventh level. 55 Upon the deenergization of the slow acting relay 502, ground is placed upon the wipers 520 and 521. As there is no conflict between the exchange number of Grove and any other of the exchanges, the switching discriminator has no switching function to perform. 60 However, the grounding of wiper 521 closes a circuit for the lower winding of the relay 55 in series with the relay 501 as the bank contacts accessible to the wiper 521 of the switching discriminator are connected to the conductor 525 if they have no switching function to perform. This provision is made to secure the energization of the relay 501 so that subsequent digits dialled will have no

effect on the switching discriminator. The relay 501 merely opens the circuit of the magnet 505 in order to prevent further operation of the switching discriminator. The energization of relay 55 serves to disconnect a direct bridge across the wipers 120 and 122 70 through contacts on the line relay and to substitute therefor a bridge extending through the right hand winding of the repeating coil and the left hand winding of the electro-polarized shunt field relay 51.

The succeeding operations of the fourth selector 4E¹, a fifth selector 5E¹, and a connector, such as H⁴ in the Grove exchange, 80 take place in a manner similar to that already described in response to the four remaining digits 648x. As before, the connection is released by the replacement of the receiver at the calling substation A.

Having described the operations of extending connections from the Center exchange, to 85 subscribers in the exchanges in various other districts, as well as in the same district as Center exchange, the manner in which a connection local to Center exchange is established will now be described. For this purpose it will be assumed that the calling subscriber at substation A desires to communicate with the subscriber at substation A¹. In order to do this, the calling subscriber will remove his receiver and operate his calling device in accordance with the number CENTER-245x.

The removal of the receiver at substation A causes the trunk selecting operation of the primary line switch C to take place in the 100 usual manner. Assuming that the trunk line shown in the drawings terminating in bank contacts 28-30, inclusive, is the one selected, the calling line will be extended to the line relay 56 of the selector repeater 1E.

The line and release relays of this switch, upon energizing, operate in the usual manner to prepare the circuits of the selector repeater for operation, and to ground the release trunk conductor 103 to establish a holding circuit 110 for the line switch C.

In response to the operation of the calling device for the first digit C, the circuit of the line relay 56 is operated twice and two impulses of current are sent to the vertical magnet 62 through the slow acting relay 58. Magnet 62 operates to raise the two sets of switch wipers opposite the second level of bank contacts. The slow acting relay 58 operates in the usual manner to close the circuit for the stepping relay 59 and, upon deenergizing, shortly after the termination of the vertical movement of the switch, initiates its rotary trunk selecting movement. The trunk selecting operation of the selector repeater 1E now takes place in the usual manner. As there is no conflict between the exchange name Center and any of the other

5 exchanges in the system there is no trunk selecting operation of the switch, the switch wipers merely rotating in on the first contact set on the second level, whereupon the switching relay 60 energizes. Upon operating, relay 60 prepares an impulsing circuit for the switching discriminator.

10 The next two characters EN when dialled on the calling device, operate the vertical magnet 506 and rotary magnet 505 of the switching discriminator SD, whereby the switch wipers 520 and 521 are brought opposite the third level of bank contacts and are then rotated into engagement with the 15 sixth contact set therein. The slow acting relay 502, of course, energizes in series with the rotary magnet, and shortly after the termination of the rotary movement of the switching discriminator, deenergizes to 20 ground wipers 520 and 521. The grounding of the wipers 520 and 521 completes a circuit for the lower windings of relays 54 and 55 in the selector repeater 1E in series with the relay 501. Relay 501 operates to open the 25 rotary magnet circuit of the switching discriminator as before, while relays 54 and 55 merely operate to disconnect both sets of switch wipers from the selector repeater. The grounding of wiper 521 causes a circuit to be 30 completed extending from the lower bank contact 36, conductor 147, and through the winding of the relay 53, to battery. Relay 53, upon energizing, at its armature 74 places ground upon the conductor 157, and at armatures 72 and 75 disconnects both sets of switch 35 wipers, and at the front contacts of these armatures extends the connection over the conductors 156 and 158 to the rotary secondary line switch C³. The grounding of conductor 157 causes the energization of line 40 relay 550 of line switch C³. Relay 550 causes the line switch C³ to operate to select an idle trunk line. Assuming that the trunk line shown in the drawings terminating in bank contacts 564-566, inclusive, is the one 45 selected, the switching relay 551 is energized immediately upon the switch wipers 560-562, inclusive, being brought into engagement with this set of bank contacts. Relay 551, upon operating, places ground upon the test contact 565 in order to busy the seized trunk 50 line and, at armatures 552 and 555, extends the connection to the windings of the line relay 600 of the local fourth selector 4E² in Center office.

55 The line relay 600 is immediately energized and operates to close the circuit of the slow acting relay 601. The latter relay, upon attracting its armatures, prepares the operating circuits of the switch and places ground upon the release trunk conductor 569 thereby completing a holding circuit for the switching relay 551 of the secondary line switch C³ in the usual manner.

When the next digit 2 is dialled by the calling subscriber, two interruptions are produced in the line circuit of the line relay 56. This relay operates to repeat these interruptions to the line relay 600 of the fourth selector 4E. The line relay 600 controls the 65 operation of the vertical magnet of the fourth selector in raising the switch wipers opposite the second level of bank contacts. The trunk selecting movement of the fourth selector 4E² now takes place. Assuming that the 70 trunk line terminating in bank contacts 611-613, inclusive, is the one selected, as soon as the wipers 607-609, inclusive, are associated with this set of bank contacts, the switching relay 606 energizes. Upon operating, relay 606 places ground upon the test contact 612 in order to busy the seized trunk line and also extends the connection to the line relay 625 in the fifth selector 5E².

75 In response to the next digit 4, the line relay 56 of the selector repeater 1E repeats the interruptions to the line relay 625 of the fifth selector. The wipers 630-632, inclusive, of the fifth selector 5E² are raised opposite the 80 fourth level of bank contacts and are then rotated into engagement with a bank contact set associated with an idle trunk line in substantially the same manner as the fourth selector 4E² operated. It will be assumed that the trunk line terminating in bank contacts 90 634-636, inclusive, is the one selected. The switching relay 627 of the fifth selector energizes to extend the connection to the line relay 651 of the connector H.

95 The line and release relays 651 and 652 of this switch, operate in the usual manner performing several functions, among which is to establish a holding circuit for the secondary line switch C³, the fourth selector 4E², and the fifth selector 5E².

100 The connector H³ operates in the same manner as the connector H operated to establish the desired connection with the line of the substation A¹, terminating in bank contacts 660-662, inclusive, in response to the last two 105 digits 5x.

110 All the apparatus involved in the connection is released by the calling subscriber at substation A replacing his receiver upon the switch-hook.

115 It will be noted that in connections local to district B where the call originates, second and third selectors are saved when it is unnecessary to trunk through a plurality of offices by the use of switching discriminators 120 such as SD.

125 What is claimed is:

1. In a telephone system, a switching device, a plurality of exchanges, a group of trunk lines extending to each exchange accessible to said switching device, and means for operating said switching device in accordance with a digit of a called number to

seize a trunk line in each one of said groups simultaneously.

2. In a telephone system, a switching device, a plurality of exchanges, a group of 5 trunk lines extending to each exchange accessible to said switching device, means for operating said switching device in accordance with a digit of a called number to seize a trunk line in each one of said groups simultaneously, 10 an automatic switch in each exchange, and means controlled over the seized trunk lines for operating all of said switches.

3. In a telephone system, an automatic 15 switch, a plurality of sets of wipers for said switch, groups of trunk lines accessible to each set of wipers, and means for operating said switch to move said wiper sets simultaneously and cause each of said wiper sets to seize a trunk line in one of the associated 20 groups.

4. In a telephone system, an automatic switch, a plurality of sets of wipers for said switch, groups of trunk lines accessible to each set of wipers, means for operating said 25 switch to cause said wiper sets simultaneously to seize trunk lines in two of the associated groups, means for partially extending a connection over each seized trunk line, and means for releasing all of said partially established 30 connections except the one over which the connection may be completed to the called telephone line.

5. In a telephone system, an automatic 35 switch, a plurality of exchanges, trunk lines accessible to said switch extending to each exchange, means for directly operating said switch to select said exchanges, means for automatically operating said switch to seize a trunk line extending to each of said 40 exchanges simultaneously, and means for subsequently releasing all said trunk lines except one.

6. In a telephone system, an automatic 45 switch, a plurality of exchanges, trunk lines accessible to said switch extending to each exchange of said plurality, means for directly operating said switch to select said exchanges, means for automatically operating said switch to seize a trunk line extending to 50 each of said exchanges simultaneously, means for sending impulses over said seized trunk lines in accordance with digits in a called number to operate automatic switches in each of said exchanges, and means for subsequently 55 releasing all said trunk lines except one.

7. In a telephone system, a number of exchanges, an automatic switch, trunk lines extending to each of said exchanges accessible to said switch, means for operating said 60 switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all said trunk 65 lines and operated switches if certain predetermined series of impulses are sent over said trunk lines.

8. In a telephone system, a number of exchanges, an automatic switch, trunk lines 70 extending to each of said exchanges accessible to said switch, means for operating said switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all said trunk 75 lines except the one over which connection with the desired called line may be established as determined by the impulse series sent over said trunk lines.

9. In a telephone system, a number of exchanges, an automatic switch, trunk lines 80 extending to each of said exchanges accessible to said switch, means for operating said switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all of said trunk lines except the one over which connection with the desired called line 85 may be established as determined by the impulse series sent over said trunk lines.

10. In a telephone system, a number of exchanges, an automatic switch, trunk lines 90 extending to each of said exchanges accessible to said switch, means for operating said switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all of said trunk lines, a second auxiliary switch associated with said first automatic switch, another group of trunk lines accessible to said second auxiliary switch, and means operative upon said releasing operation for causing said second auxiliary switch to seize a trunk line in said other group. 95

11. In a telephone system, a number of exchanges, an automatic switch, trunk lines 100 extending to each of said exchanges accessible to said switch, means for operating said switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all of said trunk lines, a second auxiliary switch associated with said first automatic switch, another group of trunk lines accessible to said second auxiliary switch, and means operative upon said releasing operation for causing said second auxiliary switch to seize a trunk line in said other group. 105

12. In a telephone system, a number of exchanges, an automatic switch, trunk lines 110 extending to each of said exchanges accessible to said switch, means for operating said switch to seize trunk lines extending to a plurality of said exchanges simultaneously, automatic switches in said exchanges, means for sending impulses over the seized trunk lines to operate a series of said switches in each exchange to extend a connection in the direction of a called line, an auxiliary switch associated with the first mentioned automatic switch and operated in synchronism with the switches in said exchanges, means controlled by said auxiliary switch for releasing all of said trunk lines, a second auxiliary switch associated with said first automatic switch, another group of trunk lines accessible to said second auxiliary switch, and means operative upon said releasing operation for causing said second auxiliary switch to seize a trunk line in said other group. 115

120

125

5 by said auxiliary switch for releasing all of said trunk lines, a second auxiliary switch associated with said first automatic switch, another group of trunk lines accessible to
 10 said second auxiliary switch, means responsive to said releasing operation for causing said second auxiliary switch to seize a trunk line in said other group, and means for there-after sending impulses over the last seized
 15 trunk line to control the establishment of the connection with the desired called line.

11. In a telephone system, an automatic switch, wipers for said switch, groups of trunk lines accessible to said wipers, a plural-
 15 ity of auxiliary switches associated with said automatic switch, means for normally oper-
 20 ating said automatic switch to cause said wipers to seize a trunk line in any desired one of said groups, and means operative there-
 25 after for releasing the seized trunk line and for operating one of said plurality of auxili-
 30 ary switches.

12. In a telephone system, an automatic two-motion switch, trunk lines accessible to
 25 said switch, and means for operating said switch in said motions, successively to select and connect with a plurality of said trunk lines simultaneously.

13. In a telephone system, an automatic switch, a plurality of sets of wipers for said switch, groups of trunk lines accessible to each set of wipers, and means for operating said switch to cause said wiper sets to select and connect with trunk lines in a plurality
 35 of said groups simultaneously.

14. In a telephone system, an automatic switch, a plurality of sets of wipers for said switch, groups of trunk lines accessible to each set of wipers, means for operating said switch to cause said wiper sets to select and connect with trunk lines in a plurality of said groups simultaneously, and means for sending impulses over the seized trunk lines corresponding to digits in a called telephone
 45 number.

15. In a telephone system, an automatic switch, a plurality of sets of wipers for said switch, groups of trunk lines accessible to each set of wipers, means for operating said switch to cause said wiper sets to select and connect with trunk lines in a plurality of said groups simultaneously, means for sending impulses over the seized trunk lines corresponding to digits in a called telephone number, and means operative if certain predetermined digits are sent for releasing all of said trunk lines except one.

16. In a telephone system, an automatic switch, a plurality of sets of wipers for said switch, groups of trunk lines accessible to each set of wipers, means for operating said switch to cause said wiper sets to select and connect with trunk lines in a plurality of said groups simultaneously, means for sending impulses over the seized trunk lines cor-

responding to digits in a called telephone number, means operative if certain predetermined digits are sent for releasing all of said trunk lines, another group of trunk lines, and means operative upon such release for seizing
 70 a trunk line in said other group.

17. In a telephone system, an automatic two-motion switch, groups of trunk lines accessible to said switch, a plurality of exchanges, each of said groups extending to one
 75 of said exchanges, and means for operating said switch in said motions, successively, to select and connect with a trunk line in a plurality of said groups simultaneously.

18. In a telephone system, an automatic two-motion switch, groups of trunk lines accessible to said switch, a plurality of exchanges, each of said groups extending to one
 80 of said exchanges, and means for operating said switch in said motions, successively, to
 85 select and connect with a trunk line in a plurality of said groups simultaneously or for operating said switch to seize a trunk line in only one of said groups, depending upon the digit in a called telephone number.

19. In a telephone system, a plurality of groups of trunk lines, an automatic switch having a directly controlled primary movement to select a desired group of trunk lines and having a free hunting secondary movement to find an idle trunk line in the selected group, a plurality of auxiliary switches individual to said automatic switch and having access each to a separate group of other trunk lines, means for operating said automatic switch to extend a connection over one
 95 of the first mentioned trunk lines, and means responsive to further directive control for releasing the seized trunk line and for operating one of said auxiliary switches to extend
 100 a connection through an associated trunk line.

20. In a telephone system, a plurality of groups of trunk lines, means for extending a connection over a trunk line in any desired
 110 group, another group of trunk lines, and means effective in case a certain digit combination is contained in the desired telephone number for releasing the seized trunk line and for extending a connection over a trunk line in said other group.

21. In a telephone system, a plurality of groups of trunk lines, means for extending a connection over a trunk line in any desired group, a plurality of groups of other trunk lines, and means effective in case the called telephone number contains any one of a plurality of digit combinations for releasing the extended connection and for extending a new connection through one of said other trunk lines, the group used to extend the last named connection depending upon the particular one of said digit combinations contained in the desired number.

22. In a telephone system, an automatic

switch, other similar automatic switches, pairs of non-numerical switches accessible to all said automatic switches, means for operating said automatic switch to seize an idle 5 pair of said non-numerical switches, two groups of trunk lines accessible, respectively, to the seized pair of non-numerical switches and similarly accessible to the remaining pairs, means responsive to the seizure of said 10 pair of non-numerical switches for operating each of them to seize a trunk line in the associated group, and means in said automatic switch for subsequently bringing about the unseizure of only one of the trunk lines seized 15 by said pair of non-numerical switches, while maintaining both of said non-numerical switches non-selectable to said other automatic switches.

23. In a telephone system, an automatic 20 trunk hunting switch having a plurality of sets of wipers, a set of trunk lines accessible to said plurality of sets of wipers, other sets of trunk lines also accessible to said plurality of sets of wipers, means for operating said 25 switch to seize a set of trunk lines, and testing means whereby the seizure of a particular set of trunk lines is prevented in case any trunk line in the set tests busy.

24. In a telephone system, an automatic 30 switch, a plurality of lines accessible to said switch, and means for preventing said switch from extending connection to any of said lines in case any one of them is busy.

25. In a telephone system, an automatic 35 switch, a plurality of sets of trunk lines accessible to said switch, means for operating said switch to connect with an idle set of trunk

lines, and means for preventing said switch from connecting with a set of trunk lines in case any one of the trunk lines in the set is in 40 use.

26. In a telephone exchange system, a calling subscriber's line, a group of lines of one character, a group of lines of another character, an automatic switch, means under 45 the control of said calling line for operating said automatic switch to independently connect an idle one of each of said group of lines to said calling line.

27. In a telephone exchange system, an 50 automatic switch, a calling subscriber's line associated with said automatic switch, a group of lines of one character accessible to said switch, a group of lines of another character accessible to said switch, and means under 55 the control of said subscriber's line for operating said automatic switch to simultaneously select an idle one of each of said group of lines.

28. In an automatic telephone system, an 60 exchange including two automatic switches, groups of trunks leading to different exchanges accessible by way of the first of said switches, trunks local to the exchange accessible by way of the second switch, means 65 for extending a connection to the first switch, and means controlled through the first switch and effective if a telephone number local to the exchange is called for releasing the first switch and for extending a connection through 70 the second switch.

In witness whereof, I hereunto subscribe my name this 29th day of May, A. D. 1922.

CLARENCE E. LOMAX.
